UNITED STATES PATENT OFFICE.

WALTER B. STRICKLER, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed March 19, 1921. Serial No. 453,724.

To all whom it may concern:

Be it known that I, WALTER B. STRICKLER, a citizen of the United States, residing at East Orange, in the county of Essex, State 5 of New Jersey, have invented certain new and useful Improvements in Telephone-Exchange Systems, of which the following is a full, clear, concise, and exact description.

This invention relates to telephone exchange systems, and more particularly to a 10 cord circuit arrangement for establishing connections between telephone lines.

One of the objects of the invention is to provide an improved cord circuit arrangement 15 for establishing connections between extension lines of a private branch exchange, and between such extension lines and trunk lines leading to a main central office, which central office may be either of 20 the manual or machine switching type.

Another object of the invention is to provide a cord circuit of the character just described, which is so arranged that in the establishment of incoming connections between 25 trunk lines extending from the main central office and extension lines, non-through supervision will be provided, after the connection to the extension line is established, or in other words the subscriber upon 30 the extension line will have control of the supervisory apparatus at the private branch exchange only, and the operator will have control of the supervisory apparatus at the main central office.

Another object of the invention is to provide a cord circuit of the character above described, in which where a subscriber at the private branch exchange hangs up the receiver after being connected to a trunk line 35 leading to the central office, the trunk line will be freed automatically for an incoming call from the main central office, and the cord circuit will be opened to prevent a ringing signal incoming from the main central office over the trunk line from ringing the bell of the subscriber at the private branch exchange, in case the connection has not been taken down.

Another object of the invention is to provide a cord circuit of the character above described, which is so arranged that in the establishment of outgoing connections between extension lines and trunk lines leading to the main central office, through super-

vision will be provided after the connection 55 to the trunk line is established, or in other words the subscriber upon the extension line will have control of supervisory apparatus at the main central office as well as the supervisory apparatus at the private branch 60 exchange.

One of the features of the invention consists in the provision of means whereby on all calls over the trunk lines through supervision will be provided except in those cases 65 in which a ringing key is actuated at the operator's position to call a private branch exchange station.

Another feature of the invention consists in the provision of means whereby a private 70 branch exchange subscriber can transfer a call which is incoming over the trunk line without actuating the supervisory apparatus at the main central office.

These objects as well as other objects of 75 the invention may be attained by means of the arrangement set forth in the following description and illustrated in the accompanying drawing, the figure of which illustrates a circuit diagram of one embodiment 80 of the invention.

Referring to the drawing, a cord circuit C for establishing connections at a private branch exchange is shown terminating in plugs 15 and 50. The plug 15 is adapted to 85 co-operate with the jack 10 of a trunk line T leading to the main central office, or with jacks, such as 75, of extension lines, such as L², leading to individual stations of the private branch exchange. The plug 50 is also 90 adapted to cooperate with jacks, such as 51, of extension lines, such as L³, extending to individual stations of the private branch exchange. The trunk line T may terminate at a main central office at which connections 95 are established either manually or by means of machine switching apparatus. Ringing keys FK and BK are associated with the front and back cords terminating in the plugs 15 and 50, respectively, for ringing the stations connected to the private branch exchange when local connections are established. A key LK is also provided for 100 associating the operator's set with the cord circuit, the key being so arranged that when operated the conductors of the front and back cords, instead of being directly connected together, are interconnected through

105

the operator's set, the operator's set being provided with the usual transmitter M and the receiver R, and in addition, an impulse sender or dial S which is provided in order 5 that the operator may establish connections by means of the machine switching apparatus at the main central office.

Assuming that a subscriber at the main central office desires to be connected to a 10 subscriber at one of the extensions, as, for example, the extension L^3 of the private branch exchange, ringing current will be transmitted over the trunk line T from the main central office, thereby energizing the 15 left-hand winding of relay 11. Relay 11 upon being energized, closes a locking circuit through its right-hand winding, and also closes a circuit for the trunk line signaling device 12, both circuits extending 20 through the lower contact of the jack 10. The operator at the private branch exchange, upon observing the glowing of the lamp 12 inserts a plug 15 into the jack 10, thereby 25 opening the lower contact of the jack 10 and extinguishing the lamp 12. A circuit is now extended from battery, through resistance 13, sleeve contacts of the jack 10 and plug 15, and thence through the winding of relay 24 and non-inductive resistance 30 78 in parallel to ground. Normally, battery is supplied to the tip and ring conductors of the cord circuit C over the inner back contacts of relay 24 and the upper and lower windings of impedance coil 16. When relay 24 is energized, however, in response to 35 the answering of an incoming call over the trunk T, the battery supply connections are open, and the tip and ring conductors leading to the plug 15 are connected together 40 through the upper and lower windings of the impedance coil 16 by a connection extending over the inner left-hand alternate contacts of relay 24 and outer left-hand contacts of relay 47. A bridge is thus es- 45 tablished across the cord circuit for tripping the machine ringing apparatus at the main central office, in the manner well known in the art. Relay 24 also operates to short-circuit at its outer right-hand contacts, the 50 winding of the supervisory relay 25, which is connected in the ring conductor of the front cord.

The operator may now actuate the key LK 55 in order to connect her set with the cord circuit. When the key LK is in normal position, the tip conductors of the front and back cords are connected by a path extending from the tip contact of the plug 15, over the upper normal contacts of key FK, upper 60 normal contacts of key LK, conductor 92, upper normal contacts of relay 28, upper normal contacts of key BK to the tip contact of the plug 50. In a similar manner, a path extends from the ring contact of the 65 plug 15, lower normal contacts of key FK,

outer right hand contacts of relay 24, lowermost normal contacts of key LK, conductor 93, lower normal contacts of relay 28, through the winding of supervisory relay 34 and serially connected resistances, 30 and 70 31, in parallel, lower normal contacts of key BK to the ring contact of plug 50. When the key LK is actuated however, the circuit above described is changed, so that the tip conductors of the front and back cords are 75 connected over a path extending from conductor 92, through the uppermost alternate contacts of key LK, upper normal contacts of relay 58, contacts 90 of key LK, and thence over the path previously traced. The 80 ring connections on the other hand, extend from conductor 93, through the lowermost alternate contacts of key LK, lower normal contacts of relay 58, contacts 94 of key LK, and thence over the path previously traced. The 85 operator's talking and listening set comprising transmitter M and receiver R respectively, and the associated induction coil 98 are bridged across the circuit just described so that the operator is enabled to converse 90 with the calling subscriber or operator at the distant central office to determine what extension line is desired.

The operator upon obtaining this information and ascertaining that a connection to the extension L^3 is desired, restores the listening key LK to normal and inserts the plug 50 in the jack 51, thereby closing a circuit from ground, over the sleeve contacts of the jack 51 and plug 50, armature and back contact of relay 34, and to grounded battery, through the lamp 40, which is now caused to glow. The operator may then actuate the ringing key BK to transmit ringing current to the desired subscriber, which closes a circuit for relay 48 as follows: ground, lowermost contacts of key BK, winding of relay 48, and inner right-hand alternate contacts of relay 24 to grounded battery. Relay 48 in operating locks up over a path extending from grounded battery, inner right-hand alternate contacts of relay 24, winding and inner right-hand contacts of relay 48 to ground. Relay 48 in attracting its left-hand armature opens the locking circuit for relay 47, which relay is energized in a manner which will be hereafter described. 110

Upon the response of the subscriber at the station associated with extension L^3 , a supervisory circuit is completed from the subscriber's station through the cord circuit at the private branch exchange and over the trunk line leading to the main central office. This circuit may be traced as follows: from grounded side of the battery (not shown) at 120 the main central office, over the tip conductor of the trunk line T, tip contacts of the jack 10 and plug 15, upper normal contacts of key FK, uppermost normal contacts of key LK, conductor 92, upper normal contacts 125 130

of relay 28, upper normal contacts of key BK, tip contacts of plug 50 and jack 51, through the substation loop, ring contacts of jack 51 and plug 50, resistances 31 and 30, 5 and the winding of supervisory relay 34 in parallel, lower normal contacts of relay 28, conductor 93, lowermost normal contacts of key LK, outer right-hand armature and front contact of relay 24, lower normal contacts of key FK, contacts of plug 15 and jack 10, and thence over the ring conductor of the trunk line T to battery (not shown) at the main central office. As is well known, the circuit over the trunk line T, if said line 10 leads to a manual office, may include a supervisory relay in a cord circuit in the main central office. In case the main central office is of the machine switching type, a relay corresponding somewhat in function to the 15 supervisory relay will be included in the machine switching circuit. The supervisory relay at the main central office will, on an incoming call, be under the control of the operator of the private branch exchange. 20 The supervisory relay 34 upon being energized opens the circuit of lamp 40 and closes a circuit through relay 47, which may be traced as follows: grounded battery, inner right-hand alternate contacts of relay 24, 25 winding of relay 47, front contact and armature of relay 34, sleeve contacts of plug 50 and jack 51 to ground. Relay 47, in attracting its outer right-hand armature prepares a circuit for relay 28; in attracting its inner 30 left-hand armature, short-circuits the non-inductive resistance 30 shunted about the supervisory relay 34; and in attracting its outer left-hand armature substitutes for the low impedance bridge, through the upper 35 and lower windings of the impedance coil 16, a high impedance bridge comprising the upper, lower and intermediate windings of 40 impedance coil 16 in series, said bridge extending from the tip conductor of cord 45 circuit C, through the upper and intermediate windings of coil 16, outer right-hand contacts of relay 48, outer left-hand alternate contacts of relay 47, lower winding of coil 16 to the ring conductor of cord circuit 50 C. By the substitution of the high for the low impedance bridge, the shunting effect of the battery supply from the main central office to the subscriber's instrument on the extension L³ is lessened and a better transmission circuit is provided. 55

When the subscriber at the station of the extension line L³ hangs up his receiver, the supervisory circuit previously traced is opened, and consequently the supervisory 60 relay 34 is deenergized. Relay 34 in retracting its armature opens the circuit for relay 47 which relay thereupon deenergizes and again closes at its outer left-hand contacts the bridge including the upper and 65 lower windings of coil 16 across the cord

circuit. The relay 34 upon deenergization also completes a circuit from ground, through the sleeve contacts of jack 51 and plug 50, armature and back contact of relay 34 and through the supervisory lamp 40 to 70 grounded battery causing said lamp to glow to inform the private branch exchange operator that the connection is to be taken down. Due to the presence of the bridge across the cord circuit non-through supervision is attained and the machine switching apparatus at the main central office is prevented from releasing. If on the other hand, the main central office at which the trunk line T terminates, is a manual office, the supervisory 75 relay (not shown) in the cord circuit at the main central office will be prevented from releasing.

The operator at the private branch exchange noting the disconnect signal 40 may 80 remove plugs 15 and 20 from their respective jacks thereby removing the bridge from the trunk circuit T and causing the release of the switches at the main central office or of the supervisory relay thereat, depending 85 on whether the main central office is of the machine switching or manual type, in the manner well known in the art.

If the subscriber of extension line L³ should for any reason desire to transfer the 90 incoming call to another station of the private branch exchange he may flash the operator by opening and closing his line circuit, causing thereby the intermittent energization of relay 34 and the flashing of lamp 40. 95 The operator noting the flashing signal may respond and transfer the call. It will be noted that in transferring the call the low impedance bridge remains connected across the cord circuit so that the supervisory apparatus at the main central office is not affected. 100

Should a subscriber on an extension line such as L³ desire to be connected to a subscriber at the main central office, the operation is as follows. When the subscriber removes his receiver from the switchhook the line relay 52 is energized to close the circuit of the line lamp 53. The operator in response to the glowing of the line lamp will 110 insert the plug 50 of the cord circuit C into the jack 51, thereby disconnecting the line relay 52 and extinguishing the line lamp 53. As the relay 24 is not now energized, the battery supply may be traced from grounded 115 battery, over the inner right-hand normal contacts of relay 24, lower winding of impedance coil 16, conductor 93, lower normal contact of relay 28, through the winding of supervisory relay 34, and non-inductive resistances 30 and 31 in parallel, lower normal contacts of key BK, ring contacts of plug 50 and jack 51, through the calling substation loop, tip contacts of jack 51 and plug 50, upper normal contacts of key BK, upper nor- 120 125 130

4
normal contacts of relay 28, conductor 92; upper winding of impedance coil 16, and inner left-hand normal contact of relay 24 to ground. The supervisory relay 34 is energized over the circuit just traced and opens the circuit of the supervisory lamp 40, which would otherwise be closed over the sleeve contacts of plug 50 and jack 51.

The operator may now actuate the listening key LK, thereby connecting her telephone set to the cord circuit in the manner already described, so that she is enabled to converse with the calling subscriber. Upon ascertaining that the subscriber desires a connection through the main central office, the operator will insert the plug 15 into the jack 10. A circuit is now completed for relay 24 over the path previously described, which relay in operating disconnects the battery supply through the impedance coil 16, so that the current for the calling subscriber's station will now be supplied directly from the main central office. Relay 24 also short-circuits the winding of the supervisory relay 25, and at its inner right-hand alternate contacts connects battery to one side of the winding of relay 47, the other side of which is connected to ground through the contacts of supervisory relay 34 and sleeve contacts of plug 50 and contact 51. Relay 47 thereupon energizes.

Further action by the private branch exchange operator will now depend upon whether or not the main central office is a manual office or an automatic office. In case the main central office is a manual office the line relay (not shown) associated with the trunk line T at the main central office will be energized as soon as the plug 15 is inserted into the jack 10 by means of the through supervisory circuit already traced, if the listening key LK is in normal position. If the key LK is operated however, as would normally be the case under the conditions being described, a circuit for said line relay would be completed as follows: from grounded battery (not shown), through said line relay (not shown) over the ring conductor of the trunk line T, ring contacts of jack 10 and plug 15, lower normal contacts of key FK, front contact and outer right-hand armature of relay 24, contacts 94 of key LK, right-hand normal contacts of relay 60, impedance coil 59, contacts 90 of key LK, upper normal contacts of key FK, tip contacts of plug 15 and jack 10, and over the tip conductor of the trunk line T to ground (not shown) at the main central office. It will be noted that in addition to the circuit just described for the line relay at the main central office, a parallel circuit through the calling subscriber's station is provided. The operator at the distant central office being apprised through the line lamp (not shown) that a call has come in,

answers the call in the usual manner, and the private branch exchange operator through her telephone set which is connected to the cord C over the contacts of the key LK is able to converse with the operator at the main central office and inform the operator the number desired so that the operator at the main central office may complete the connection. The private branch exchange operator after having passed the call to the main central office operator, will restore the listening key LK to normal, so that the talking circuit will be the same as previously traced for a call incoming from the main central office.

In case the main central office is of the machine switching type the operator at the private branch exchange after having inserted the plug 15 into the jack 10 may then actuate the impulse sender S a number of times corresponding to the number desired at the main central office for the purpose of setting the machine switching apparatus thereat. Upon the initial movement of the dial S, off-normal contacts 69 thereof are closed, thereby completing an obvious circuit for slow-to-release relay 68, which in energizing completes an obvious circuit for relay 60. Relay 60 in attracting its left-hand armature completes an obvious circuit for relay 58 which relay in operating opens the conductive connection which had previously existed between the front and back conductors of the cord through the operator's set. Battery supply is now furnished to the extension L³ through the windings of relay 61 over a path which may be traced as follows: from grounded battery, through the lower winding of relay 61, lower right-hand winding of repeating coil 99, lower alternate contacts of relay 58, lowermost alternate contacts of key LK, and thence over the circuit previously traced through the supervisory relay 34, through the calling substation loop and thence over a path previously traced through the uppermost alternate contacts of key LK, upper alternate contacts of relay 58, upper right-hand winding of repeating coil 99, and upper winding of relay 61 to ground. Supervisory relay 34 is held energized over this circuit during the actuation of the dial and relay 61 is now energized. Relay 61 at its armature and front contact completes a holding circuit for relay 58 to maintain the connection thus established, independently of the relay 60, whose energization depends upon the dial being off-normal.

When relay 60 was energized, upon the initial movement of the dial, a dialing circuit was completed to the trunk line T from the tip conductor of said line over the tip contacts of jack 10 and plug 15, upper normal contacts of key FK, contacts 90 of key LK, interrupting contacts 70 of the dial 130

S, right-hand alternate contacts of relay 60, contacts 94 of key LK, outer right-hand armature and front contact of relay 24, lower normal contacts of key FK, ring contacts of plug 15 and jack 10, to the ring conductor of the trunk line T. The dial operates in the well-known manner to interrupt the dialing circuit just traced, and operates the machine switching apparatus

10 at the main central office.

This dialing circuit it will be noted, is independent of the supervisory circuit controlled over the extension L³. However, at the conclusion of the dialing operation, if 15 the operator for any reason should fail to restore the listening key LK, a holding circuit for the trunk line T will be provided through the impedance coil 59 in the operator's set, as this coil will be bridged across 20 the tip and ring conductors of the trunk line T. This bridge is closed by the deenergization of the relay 60, which takes place after the dial operation ceases. With the circuit in this condition the calling subscriber 25 is able to converse with the called subscriber, even though the listening key LK has not been restored by reason of the fact that the right-hand winding of induction coil 98 in the operator's set is bridged across 30 the tip and ring conductors of the cord circuit in parallel, with the impedance coil 59 as soon as the slow-to-release relay 68 is released. The repeating coil 99 serves to inductively couple the front and back conductors through the operator's set so that 35 the subscriber can talk through the repeating coil. It will be noted that the circuit of the right-hand winding of the repeating coil 99 was held open during the dialing operation by the relay 68 to prevent the noise 40 resulting from the dialing impulses being transmitted to the calling subscriber. If, as before stated, the operator fails to restore the key to normal after having dialed, 45 she is informed of her failure to do so by hearing a ringing signal before the called party answers or by hearing conversation after the called party responds whereupon she restores the key LK to normal position.

50 At the completion of conversation, the hanging up of the calling subscriber's receiver causes the release of the supervisory relay 34. If the trunk line leads to an automatic exchange, the machine switching apparatus 55 by which the connection was set up at the main central office, will be released in the manner well known in the art. If on the other hand, the main central office at which the line T terminates, is 60 a manual office, the opening of the supervisory circuit above traced, results in the deenergization of a supervisory relay (not shown) in the cord circuit at the main central office, so that the operator at such office 65 will be informed that the connection is to

be taken down. Relay 34 upon deenergization opens at its armature and front contact the original energizing circuit for relay 47. Relay 47 remains energized however, over a locking circuit including contacts 96 of key LK, left-hand contacts of relay 48, inner right-hand contacts and winding of relay 47, and inner right hand contacts of relay 24. Due to relay 47 locking (the bridge is prevented from being 70 placed across the cord circuit when relay 34 releases. The extension subscriber thus controls the release of the connection. Relay 34 in deenergizing also completes a circuit for supervisory lamp 40 over the path previously traced, causing said lamp to glow to inform the private branch exchange operator that the connection is to be taken down. Another circuit is completed at the same time for relay 28 over a path extending from 80 grounded battery, winding of relay 28, outer right-hand contacts of relay 47, back contact and armature of relay 34, and sleeve contacts of plug 50 and jack 51 to ground. Relay 28 thereupon energizes, thereby disconnecting the front from the back cord and connecting ground and battery to the tip and ring conductors respectively of the back cord. By thus opening the cord circuit, ringing current transmitted over the trunk 95 T from the main central office will not, in the extent that the private branch exchange operator delays taking down the connection, be transmitted to the extension L³ with which the cord circuit is still associated, to 100 ring the bell at the subscriber's station. The ringing response relay 26 is bridged across the front cord between the point of disconnection and the plug 15, so that this relay will respond to any ringing signal of this 105 character, and will cause the lamp 71 to glow thereby giving the private branch exchange operator a recall signal.

If the subscriber at the extension L³ should recall by taking the receiver off the 110 hook before the connection has been taken down, a circuit is provided for energizing the supervisory relay 34 due to the operation of relay 28 so that by flashing the switchhook the lamp 40 may be caused to 115 glow to attract the attention of the operator. The supervisory relay 34 when again energized by the subscriber removing his receiver before the private branch exchange operator takes down the connection, opens 120 the circuit of relay 28. Relay 28 releases and again closes the cord circuit so that the connection extends directly to the main central office, and battery for supervisory relay 34 is now supplied therefrom. With 125 the circuit in this condition the subscriber may now extend one or more calls through the distant central office without the aid or intervention of the private branch exchange operator.

If no recall signal, as has been described, should be transmitted, the private branch operator, upon observing the glowing of the lamp 40 in response to the hanging up of the receiver associated with the extension L³ will withdraw the plugs 15 and 50 from their respective jacks. By withdrawing the plug 15 the supervisory lamp 40 will be extinguished and the relay 28 will be deenergized, so that the talking conductors of the cord circuit will be restored to their normal condition. When the plug 15 is disconnected, the relay 24 is accordingly deenergized to again bridge battery across the conductors and to open the circuit of relay 47, thereby restoring the cord circuit apparatus to normal.

In case the subscriber of the extension L³ should desire to be connected with another extension L² of the same private branch exchange, the operator will insert the plug 50 into the jack 51 and actuate the listening key LK as before. Relay 24 of the cord circuit not being operated, battery is connected through the upper and lower windings of impedance coil 16 to supply current to the calling subscriber's transmitter, and to operate the supervisory relay 34. The operator upon ascertaining the number of the described subscriber's line will insert the plug 15 into the jack 75. The sleeve contact of the jack 75 being grounded, the relay 24 is not energized over the sleeve circuit as in the case previously described, and consequently battery is supplied for the called subscriber through the impedance coil 16. Relay 47 is not energized by the supervisory relay 34 during a connection of this character, for the reason that the circuit for relay 47 depends upon the energization of relay 24. The lamp 71 now functions as a supervisory lamp for the calling end of the cord circuit. A circuit is completed extending from battery, through the lamp, over the outer left-hand contacts of relay 24, back contact and armature of relay 25 and sleeve contacts of plug 50 and jack 51 to ground. When the called subscriber of the extension L² responds, the supervisory relay 25, which is included in the battery supply circuit to the called subscriber, and which is, in this instance not short-circuited by the right-hand contacts of relay 24, becomes energized and opens the circuit of supervisory lamp 71. When the two subscribers hang up, the supervisory relays 25 and 34 which are separately controlled by the two subscribers, become deenergized and the lamps 71 and 40 are again caused to glow to give the disconnect signal. While as above described, the end of the cord terminating in the plug 50 was used as an answering end, and the end of the cord terminating in the plug 15 as the calling end, the cord circuit will function equally well for the extension interconnec-

tions if the plug 15 be used as the answering plug and the plug 50 as the calling plug, since the two ends of the cord are similar so far as these connections are concerned. For local connections it will be noted also that the feature of opening the cord circuit by means of the relay 28 in response to a disconnect signal is not present.

What is claimed is:

1. In a telephone exchange system, a trunk line, a subscriber's line, a cord circuit, means for providing through-supervision over the cord circuit if calls are extended in one direction over said cord circuit, and means for providing non-through-supervision if calls are extended in the other direction over said cord circuit. 75

2. In a telephone exchange system, a trunk line, a subscriber's line, a cord circuit, means for providing through-supervision over the cord circuit if calls are extended in one direction over said cord circuit, means for providing non-through-supervision if calls are extended in the other direction over said cord circuit, and means automatically operative incident to the establishment of a connection between said trunk line and said subscriber's line via said cord circuit for converting said cord circuit from one type of supervision to the other. 80

3. In a telephone exchange system, a trunk line, a subscriber's line, a cord circuit for interconnecting said lines, normally arranged to provide through-supervision, and means responsive to an act necessary to extend an inward call over said trunk line to said subscriber's line to convert the cord circuit to non-through-supervision. 95

4. In a telephone exchange system, a trunk line, a subscriber's line, a cord circuit for interconnecting said lines arranged to provide through or non-through-supervision, and means operating automatically to convert the cord circuit from one class of supervision to the other. 100

5. In a telephone exchange system, a trunk circuit, a line circuit, a station thereon, a cord circuit connecting said trunk circuit and said line, an impedance bridge, means for connecting said bridge across the cord circuit after said station hangs up if the call is incoming over said trunk circuit, and means for preventing the bridge from being placed across said cord circuit when the station hangs up if the call is outgoing. 115

6. In a telephone exchange system, a trunk line, a subscriber's line and a cord circuit, each having a pair of talking conductors, a subscriber's station on said subscriber's line, a talking circuit including the talking conductors of each of said circuits and said subscriber's station, an impedance bridge for said cord circuit, and means for rendering said bridge effective or not when the subscriber opens the line circuit after 120 130

completion of conversation, depending upon whether or not the call is incoming or outgoing from the subscriber's station.

7. In a telephone exchange system, a 5 trunk line, a subscriber's line, a station thereon, a cord circuit for completing incoming calls over said trunk line for said station and for completing outgoing calls from said station over said trunk line, an 10 impedance bridge for said cord circuit, means for connecting said bridge across said cord circuit, after conversation is completed if the call is incoming over said trunk line and means for preventing the connection of 15 said bridge across said cord circuit after conversation is completed if the call is outgoing over said trunk line.

8. In a telephone exchange system, a trunk line, a subscriber's line, a station 20 thereon, a cord circuit for completing incoming calls to said station over said trunk line and for completing outgoing calls from said station over said trunk line, a key in said cord circuit for signaling said station 25 if the call is incoming over said trunk line, a supervisory signal in said cord circuit, a relay in said cord circuit controlled by the station for actuating said supervisory signal to inform the operator that the station signalled desires to have the connection transferred, an impedance bridge for said cord 30 circuit, and a second relay in said cord circuit controlled by said first named relay for

connecting said bridge across said cord circuit.

9. In a telephone exchange system, a private branch exchange, a plurality of extension lines extending therefrom, a trunk line extending from said exchange to a main central office, a cord circuit at the private 40 branch exchange for completing connections between an extension line and said trunk line or for interconnecting extension lines, a bridge for said cord circuit, means whereby, when said cord circuit is used in establishing 45 a connection between an extension line and said trunk line, and a subscriber hangs up, the talking conductors of the cord circuit will be opened and said bridge will be connected across the cord circuit if the call is 50 incoming over said trunk line, and means whereby the talking conductors of the cord circuit will be opened and said bridge will be prevented from being connected across 55 said cord circuit if the call is outgoing over said trunk line.

10. The method wherein calls are extended over a trunk and a cord circuit which comprises furnishing different classes of supervision depending on the direction in 60 which the call is extended.

In witness whereof, I hereunto subscribe my name this 17th day of March, A. D., 1921.

WALTER B. STRICKLER.
